(57) **CLAIM**

The ornamental design for an automobile interior design, as shown and described.

DESCRIPTION

FIG. 1 is a front, right side perspective view of an automobile interior design showing our new design;

FIG. 2 is a front, left side perspective view thereof; and, FIG. 3 is a top plan view thereof.

Features shown in broken lines with consistent dotted or dash lengths illustrate ornamentation, features, and/or environment that form no part of the claimed design.

1 Claim, 3 Drawing Sheets

FIG. 3
